[57] CLAIM

The ornamental design for a household water leak indicator, as shown and described.

DESCRIPTION

FIG. 1 is a top plan view of a household water leak indicator showing my new design;

FIG. 2 is a typical side elevational view thereof;

FIG. 3 is a bottom plan view thereof;

FIG. 4 is a top plan view of another embodiment of my new design of FIGS. 1-3;

FIG. 5 is a front elevational view thereof, the rear being a mirror image thereto;

FIG. 6 is a bottom plan view thereof.
